UNITED STATES PATENT OFFICE.

CARL A. LOHMAN, OF SEATTLE, WASHINGTON.

UNPILING DEVICE FOR LUMBER.

1,272,472.

Specification of Letters Patent. Patented July 16, 1918.

Application filed November 15, 1916. Serial No. 131,438.

To all whom it may concern:

Be it known that I, CARL A. LOHMAN, a citizen of the United States, and resident of the city of Seattle, county of King, and 5 State of Washington, have invented certain new and useful Improvements in Unpiling Devices for Lumber, of which the following is a specification.

My invention relates to lumber handling 10 devices and consists of an apparatus for use in breaking down and distributing lumber after it has been through the dry kiln. The device might thus be called an unpiling device.

15 The object of my invention is to provide means whereby the lumber may be easily and cheaply distributed and sorted and in such manner as to dispense with as much labor as possible.

20 The novel features of my invention will be hereinafter described and then particularly pointed out in the claims.

The accompanying drawings show my invention in forms of construction which are 25 now preferred by me.

Figure 1 is a side elevation of one type of construction.

Fig. 2 is a plan view of the same type of construction.

30 Fig. 3 is a side elevation of a modified type of structure.

Fig. 4 is a sectional elevation taken on a plane just within the rack bars of the construction shown in Fig. 1.

35 In the modern practice of kiln drying lumber, the lumber is assembled in piles of suitable size to make a truck load. These truck loads must be taken down and distributed and sorted. One reason for this is that 40 the entire load may not be of the same kind of lumber. Another is that the kiln drying process often causes warping, checking, and other defects in the lumber which necessitates a grading operation before storing or 45 delivery to the purchaser.

I provide an elevated support for the pile of lumber as it is removed from the kiln, this support being inclined to such a degree that there is a strong tendency for the lumber to slide down the incline. This support is shown in the drawings as beams 1. The pile of lumber is placed with its length extending across the beams.

50 To prevent sliding of the pile down the incline I provide a stop or stops, which are adjustable in height so that they may be

lowered to thereby permit single layers to slide off at a time. These slide down the incline ways 20 of the adjustable stop device to a sorting table 3.

60

The construction shown in Figs. 1 and 2 has the stop and the inclined slide ways 20 in the form of a frame which is hinged at the end opposite the pile of lumber. It has rack bars 23 at the end next to the lumber 65 pile, which are engaged and operated by the pinions 24 mounted upon a transversely extending shaft 25. This shaft is turned and controlled by any suitable means, either hand or power. I have shown hand cranks 70 26, but these are only indicative of any suitable means.

The alternative construction shown in Fig. 3 employs a rigid frame in which the beams 2 which engage the lumber pile and form 75 the stops, are straight and the frame moves alike at both ends. To secure this result both ends are provided with rack bars, 23, operated by pinions 24 on shafts 25, and the shafts at opposite ends are actuated alike 80 through some suitable transmission mechanism, as the chain 4 and wheels therefor carried by the shafts.

I have not shown any power operating connections, as this may or may not be done 85 and the manner of doing this would be a simple one for any mechanic.

The manner of operating this device is believed to be clear and to not need any further explanation.

90

What I claim as my invention is:

1. In a means for taking down and sorting a pile of lumber after drying, in combination, a sorting table, a support for the pile of lumber elevated above and removed laterally from the sorting table, said support being inclined toward the sorting table at an angle at which the lumber will slide, and inclined guideways extending from one side of the sorting table to the elevated pile of 100 lumber and engaging said pile to hold the same against sliding, and means for raising and lowering these guideways to permit the lumber to slide from the pile a layer at a time.

105

2. In a means for taking down and sorting a pile of lumber after drying, in combination, a sorting table, a support for the pile of lumber elevated above and removed laterally from the sorting table, said support being inclined toward the sorting table at an angle at which the lumber will slide, and in-

clined guideways pivoted by one end at one side of the sorting table, its other end being positioned to engage the lower side of the pile of lumber to prevent its sliding, and 5 means for raising and lowering the swinging end of said guideways to permit the lumber to slide down the same to the sorting table a layer at a time.

3. In a means for sorting lumber, a sorting table, a slideway pivoted at one side of said table and having an arcuate outer end extending downward from its upper sliding surface, elevated supports for a pile of lumber inclined toward said slideway and extending to the swinging end thereof, and 15 means for raising and lowering said slideway.

4. In a means for taking down and sorting a pile of lumber that is disposed in a number 20 of layers one above the other, the combination with a support for the pile of lumber which is disposed at such an angle as to cause the lumber to tend to slide therefrom, of a stop against which the front face of the pile of lumber abuts, means for moving the 25 stop downwardly across the face of the pile of lumber to successively uncover the several layers and inclined guides extending from the stops onto which the lumber passes and 30 by which the lumber is discharged.

5. In a means for taking down and sorting a pile of lumber that is disposed in a number of layers, one above the other, the combination with a support for the pile of lumber which is disposed at such an angle 35 as to cause the lumber to tend to slide therefrom, a receiving element for the lumber, a stop against which the front face of the pile of lumber abuts, means for moving the stop 40 downwardly across the face of the pile of lumber to successively uncover the several layers and inclined guides extending from the stop on to which the lumber passes and

by which the lumber is discharged, the said guides being so mounted as to maintain their 45 operative relation to the receiving element throughout the movement of the stop across the face of the pile of lumber.

6. In a means for taking down and sorting a pile of lumber that is disposed in a number 50 of layers one above the other, the combination with a support for the pile of lumber which is disposed at such an angle as to cause the lumber to tend to slide therefrom, a receiving element for the lumber and a 55 structure movable across the front face of the pile of lumber to successively uncover the layers thereof and comprising a plurality of spaced stops and inclined guides extending from the upper ends of said spaced stops, said guides being arranged to discharge upon the receiving element.

7. In a means for taking down and sorting a pile of lumber that is disposed in a number 60 of layers one above the other, the combination with a support for the pile of lumber which is disposed at such an angle as to cause the lumber to tend to slide therefrom, of a receiving element for the pile of lumber and a structure disposed between the receiving element and the pile of lumber and comprising spaced stops against which the front face of the pile of lumber rests and inclined guides extending from the upper 65 ends of said stops to such a point as to discharge the lumber upon the receiving element, said stops and guides being bodily movable together, means for pivoting the structure at its end adjacent the receiving element and means for imparting vertical movement to that end of the structure 70 against which the pile of lumber lies.

Signed at Seattle, Washington, this 9th day of November, 1916.

CARL A. LOHMAN.
